UNITED STATES PATENT OFFICE.

MICHAEL ROTHHIRSCH, OF VIENNA, AUSTRIA.

VALVE FOR INFLATABLE BAGS FOR FOOTBALLS.

Application filed November 26, 1923. Serial No. 677,029.

To all whom it may concern:

Be it known that I, MICHAEL ROTH-
HIRSCH, a citizen of the Republic of Austria,
residing at Vienna, Republic of Austria,
have invented certain new and useful Im-
provements in Valves for Inflatable Bags
for Footballs, of which the following is a
specification.

Valves for inflatable bags for foot balls
have already been proposed in which a coni-
cal or spherical valve body of rubber is per-
manently held against the correspondingly
shaped valve seat by elastic cords or tapes.
Such valves show the drawback that the
cords or tapes lose their elasticity after
some time and then do not hold the valve
body on its seat with a force required for
tightly closing the valve.

The object of my invention is to obviate
this drawback and with this object in view
to provide a valve for the inflatable bags of
foot balls and similar articles in which the
conical valve body of rubber co-operating
with a conical valve seat is freely suspended
on and secured to a cord or tape passing
through narrow openings in the flexible
tube of the bag to the outside thereof, so
that the valve may be closed by hand.

In the annexed drawing an embodiment
of my improved valve is shown by way of
example in vertical central section.

In the inflatable rubber bag 1 there is
secured at its opening a rubber block 2 of
any desired shape preferably by being vul-
canized into the bag, a conical recess 3 pro-
vided in the block and in permanently open
communication with the flexible tube 5
serves as the valve seat. The tube 5 is se-
cured to the outside of the bag, preferably
by means of an intermediate rubber plate 4
opposite the block 2 in the usual manner.
The conical valve body 6 within the bag is
freely suspended on and secured to a cord
or tape 7, preferably a double cord or tape,
passing through small openings 10 in the
sides of the flexible tube 5 to the outside
thereof. The cord or tape 7 enters the cen-
tral bore 8 in the valve body and is secured
to a transverse pin 9, for instance by being
wound round the same. The inner end of
the bore 8 is tightly closed by a plate 11
secured to the inner end of the valve body.
For preventing the cord or tape 7 to fully
slip into the flexible tube, any suitable
means such as a button may be attached to

its outer end. If, as shown, a double cord
or tape 7 be used it is sufficient to knot the
outer ends together on the outside of the
flexible tube 5.

When it is desired to inflate the bag, any
usual inflating pump or source of air under
pressure is connected with the outer end of
the flexible tube 5, the air under pressure
forces the valve body 6 off its seat 3 while the
cord or tape 7 prevents it from entirely fall-
ing into the bag. After pumping up the bag
to the desired extent the valve is drawn
against its seat by the cord or tape 7 and
then the air pressure within the bag holds
the valve firmly in the closed position, when
the pump or source of air under pressure is
disconnected from the flexible tube. When
the bag has to be deflated it is only necessary
to push the valve away from its seat into the
bag by means of a piece of wire or a small
rod introduced into the flexible tube 5
through its outer opening. In pumping up
the bag it is advisable to push the nozzle
of the pump or connection to the source of
air under pressure so far into the flexible
tube that the openings 10 are covered.

What I claim is:

1. In a valve for inflatable bags for foot-
balls a valve seat within the bag, a flexible
tube in permanently open connection with
the opening of the valve seat and leading to
the outside of the bag, a valve body adapted
to close the said opening in the valve seat,
a cord secured to the valve body and pass-
ing through the said flexible tube and open-
ings in the latter to the outside thereof and
means on the said cord for preventing its
outer end to slip into the flexible tube.

2. In a valve for inflatable bags for foot-
balls, a valve seat within the bag, a flexible
tube in permanently open connection with
the opening of the valve seat and leading to
the outside of the bag, a valve body adapted
to close the said opening in the valve seat,
a double cord secured to the valve body and
passing through the said flexible tube and
openings on opposite sides of the flexible
tube to the outside, the outer ends of the
said double cord being knotted together
outside the flexible tube.

3. In a valve for inflatable bags for foot-
balls a valve seat within the bag, a flexible
tube in permanently open connection with
the opening of the valve seat and leading
to the outside of the bag, a valve body

adapted to close the said opening in the valve seat a double cord threaded through a bore in the valve body and secured to the latter, means for hermetically closing the inner end of the said bore, the said double cord passing through the said flexible tube and openings on opposite sides of the flexible tube to the outside, the outer ends of the said

double cord being knotted together outside the flexible tube.

In testimony whereof I have affixed my signature in presence of two witnesses.

MICHAEL ROTHHIRSCH.

Witnesses:

CARL SONDENBERG,

VLADIMIR F. PUNFTSCH.
